DESIGN FOR A COMBINED APPOINTMENT PAD AND CLOCK

Nicholas Sandor, Haymarket, London, England,
assignor to Jacob S. Sherman, Chicago, Ill.

Application January 19, 1938, Serial No. 74,406

Term of patent 14 years

To all whom it may concern:

Be it known that I, Nicholas Sandor, a citizen of Hungary, residing at Panton House, 25, Haymarket, London, England, have invented a new, original, and ornamental Design for a Combined Appointment Pad and Clock, of which the following is a specification reference being had to the accompanying drawings, forming part thereof.

of the combined appointment pad and clock; and Figure 3 is a side view of said combined appointment pad and clock.

The printed matter and the numerals appearing at the bottom of the design of Fig. 1 are merely representative.

I claim:

The ornamental design for a combined appointment pad and clock, substantially as shown and described.

NICHOLAS SANDOR.
